ATTORNEYS.

UNITED STATES PATENT OFFICE.

FRANK H. GILBERTSON, OF LOS ANGELES, CALIFORNIA.

FLUE-PIPE SUPPORT AND INSULATOR.

Application filed December 10, 1924. Serial No. 755,014.

To all whom it may concern:

Be it known that I, FRANK H. GILBERTSON, a citizen of the United States of America, and a resident of Los Angeles, in the county of Los Angeles and State of California, have invented certain new and useful Improvements in Flue-Pipe Supports and Insulators, of which the following is a specification.

10 My invention relates to and has for its purpose the provision of a combined support and insulator for flue pipes for gas heaters and the like which operates to center, effectively support, and maintain a flue pipe in proper spaced relation to the inflammable parts of the ceiling and roof of a building whereby a passage around the flue pipe is provided through which air is free to circulate, thus reducing to a minimum the possibility of fire. It is also a purpose of my invention to provide a flue pipe support and insulator which in addition to possessing the desirable qualities of simplicity, durability and inexpensiveness, is capable of application to the two ends of a flue pipe, and in practice the device at the lower end of the pipe supports the latter, while the device at the upper end of the pipe is inverted to receive, center and hold the pipe in spaced relation to the inflammable parts of the roof through which it extends.

I will describe only one form of pipe support and insulator embodying my invention and will then point out the novel features in claims.

In the accompanying drawings,

Figure 1 is a view showing in vertical section one form of flue pipe support and insulator embodying my invention in applied position with respect to a flue pipe;

Figure 2 is an enlarged transverse sectional view taken on the line 2—2 of Figure 1;

Figure 3 is a perspective view of the device shown in the preceding views.

Referring specifically to the drawings, in which similar reference characters refer to similar parts, my invention, in its present embodiment, is shown in Figures 1 and 2 as comprising a body 15 formed of sheet metal or other suitable material which, in the present instance, is circular and hollow, one end of the body being formed with a flange inturned to provide an annular collar 16. The collar 16 is formed at circumferentially spaced intervals with openings 17,

and its inner peripheral edge is bent inwardly and downwardly to form an annular lip 18. Within the body 15 are arranged a plurality of retaining members 19. In the present instance I have shown three retaining members spaced 120° apart and each member comprising a leaf spring secured at its ends by rivets or other suitable fastening members 20, while its intermediate portion is bowed inwardly so as to engage the periphery of a flue pipe inserted therein.

As shown in Figure 3, the opposite end of the body 15 is split at intervals as indicated at 21, to provide tongues 22 which can be bent outwardly at right angles to the periphery of the body to provide attaching means for securing the body to a support. In practice, the body 15 is covered with a jacket 23 of asbestos or other suitable material for the purpose of preventing the radiation of heat through the body to the parts of a building with which the device contacts when in applied position.

Referring now to Figure 1, I have here shown a conventional form of flue pipe including a lower section 24 and an upper section 25, the former being supported in upright position by one of the combined supports and insulators embodying my invention. In the applied position of the device it is inverted so that the collar 16 is disposed at the lower end of the body 15 to engage the lower end of the pipe 24 and support the latter. The lip 18 is disposed inwardly of the pipe end, as illustrated, and thus serves to properly center the pipe within the body. However, the retaining members 19 co-operate with the lip 18 in confining the pipe against lateral movement within the body and to thus maintain the pipe in properly spaced relation to the body so as to provide between the two a circular passage 26 through which air is free to circulate. The perforations 17 in the collar 16 allow the passage of air upwardly into the chamber 26. The body 15 is securely held in the ceiling of the building by driving through the angularly disposed tongues 22 nails or other suitable fastening members, the latter puncturing adjacent parts of the ceiling structure whereby the device as a unit is firmly held within the opening of the ceiling.

To maintain the upper pipe section 25 in proper spaced relation to the roof of the building, another combined support and insulator is provided which in applied posi-

tion occupies the same position as has been illustrated in detail in Figure 3. In this position, the retaining members 19 frictionally grip the upper end of the pipe section 25 and co-operate with the lip 18 in maintaining the pipe properly centered within the body so that an annular chamber or passage 27 is provided between the pipe and body through which air is free to circulate upwardly therethrough, the air passing out of the chamber through the perforations 17. With the two devices applied as just described, it will be manifest that they co-operate in firmly supporting the pipe sections in upright position and in maintaining the same in spaced relation with respect to the adjacent inflammable parts of the ceiling and roof, so as to allow the free circulation of air therebetween and thus reduce to a minimum the possibility of fire. What heat is conducted from the pipe through the body of the device is prevented from being transmitted to the adjacent parts of the building structure by virtue of the jacket insulating material 23.

Although I have herein show and de-

scribed only one form of flue pipe support and insulator embodying my invention, it is to be understood that various changes and modifications may be made without departing from the spirit of my invention and the spirit and scope of the appended claims.

I claim as my invention:

1. A support for flue pipes comprising a hollow body having one end bent over to form a collar and inwardly to provide an annular lip on the inner periphery of the collar, said collar formed with circumferentially spaced openings, resilient members for movably holding the pipe in said body, a heat insulating jacket enclosing said body and the opposite end of the body being split at intervals to form bendable tongues.

2. A support for flue pipes comprising a hollow body, a collar formed on one end of the body, an annular lip on the inner periphery of the collar, and retaining members in the body, each comprising a resilient element adapted for frictionally engaging the pipe and co-operating with the lip to center the pipe in the body.

FRANK H. GILBERTSON.
